CONTAINER

Richard R. Walton, Wellesley, John J. Austin, Milton, and Gordon E. Gott, Arlington Heights, Mass., assignors of one-half to Container Corporation of America, Chicago, Ill., a corporation of Delaware, and one-half to Dewey and Almy Chemical Company, Cambridge, Mass., a corporation of Massachusetts

Application May 17, 1941, Serial No. 394,006

5 Claims.

(Cl. 229—14)

This invention is concerned with vapor-proof storage and shipping containers. The new container is particularly useful in connection with frozen foods but may be used at other temperatures to protect any product which must be maintained in completely stable atmospheric condition.

Among the objects of the invention are to provide a storage and shipping container for substances which suffer either from gain or loss of moisture and in which such substances may be shipped and stored without change; to provide an inexpensive shipping and storage container which will eliminate loss of moisture from foodstuffs throughout the time of their frozen storage; to conserve storage space; to provide a dispensing container for retailers which may be resealed; to protect the remaining foodstuffs after the sale of one of the individual packages; to avoid the labor and expense of protecting individually each retail package; and to provide both a mechanism and a process whereby groups of retail packages may be protected against moisture loss.

Food, such as peas, green and Lima beans, and fish fillets, for example, are usually prepared for frozen storage by packing them in cardboard containers holding 12 ounces or somewhat larger quantities. The packages are then overwrapped with cellulose or wax paper sheets and frozen and stored. It is extremely difficult and quite expensive to seal long margins of sheet stock in a completely vapor-proof manner and neither cellulose sheet nor wax paper is completely vapor-proof. Consequently, foodstuffs, although better protected than if left exposed to the atmosphere, lose moisture and deteriorate slowly as the months in storage pass.

In carrying out our invention, we take advantage of the fact that certain materials, such as rubber, sheets of latex rubber, rubber hydrohalide, polyvinyl acetals and other of the newer elastomers form substantially vapor-proof films at certain temperatures. Their range of maximum impermeability, however, is a specific characteristic of the material. In the case of latex rubber, the film remains flexible but is substantially impermeable to water and gas at refrigeration temperatures.

We form a bag or sack of such a material and force it by fluid pressure into full contact with the wall portion of a shipping carton to form a vapor- and gas-tight lining. Further, to prevent shrinking, pulling away or dimensional change from occurring in the sack, we line the sack with

a stiff, close fitting lining which maintains the relative position of all parts permanently. We have selected a container suitable for frozen foods as our preferred example. For this use, 5 sheet latex rubber is the preferred substance. Consequently, in the following description, the words "rubber," "rubber latex," etc., are to be taken as illustrative of an operative material and we do not intend that a limitation to the specific material shall be implied.

Figure 1 of the drawings shows in perspective a presently preferred form of exhaust box and a fiberboard outer container about to be inserted in operative position within the box;

15 Figure 2 illustrates the next step in forming a multiwalled container in accordance with our invention and shows the way in which a bag of elastic material is stretched over the upper edge of the outer container;

20 Figure 3 is a similar view, partly in section, showing the way in which the bag stretches when vacuum is applied to the exhaust box;

Figure 3a is an enlarged sectional view showing the detailed construction of the exhaust box and of the exhaust pipe associated therewith.

25 Figure 4 shows a preferred form of inner lining in accordance with our invention.

Figure 5 shows the manner in which the bottom flaps of the liner of Figure 4 are infolded; 30 Figure 6 shows the liner of Figure 5 after it has been collapsed to facilitate insertion into the elastic bag;

Figure 7 shows the collapsed liner of Figure 6 about to be inserted into the elastic bag while the latter is stretched as shown in Figure 3;

35 Figure 8 shows the multiwalled container after the flaps on the inner lining have been pushed down to substantially coplanar position;

40 Figure 9 illustrates the removal of the multiwalled container from the exhaust box after the vacuum has been released;

Figure 10 shows the multiwalled container after the bottom flaps have been closed and sealed, in this instance, by the use of tape;

45 Figure 11 shows the multiwalled container after it has been filled with the desired product;

Figure 12 illustrates the manner in which the contents of the bag can be evacuated;

50 Figure 13 illustrates the manner of forming a twist seal in the neck of the bag;

Figure 14 shows the mouth of the bag stretched over one flap of the outer container so as to maintain the twist seal; and

55 Figure 15 shows the filled multiwalled con-

tainer just before the top flaps are closed and sealed.

We provide an exhaust box or receptacle 10 having a base 11 and upstanding walls 12. The top is open but around its inside margin we place a peripheral gasket of rubber 13. Preferably, the box 10 is made of sheet metal and preferably also the rubber gasket 13 is retained by bending over the margins of the walls 12 and pinching the rubber between the inturned margin and the wall. The air exhaust connection 15 projects a short distance into the receptacle 10 and is cut on a bevel, as the small section Figure 3a shows. This expedient prevents the carton and the sack which are later inserted from shutting off the flow of air, but other means, such as studs, on the walls 12 located below the gasket 13, or air permeable pads of burlap similarly located, are equally effective.

As Figure 1 shows, a carton 16, for example one made of corrugated fibre board having its bottom flaps 17 extended and generally occupying the plane of the walls 22 of the carton, is pushed into the open end of the exhaust box 10. The top flaps 18 of the carton are bent outwardly and turned down against the carton walls 22 and then, as shown in Figure 2, the mouth portion 19 of an extensible and flexible sack 21 is snapped over the open end of the carton 16 in such a manner that the end is completely closed by the sack. A valve not shown is then opened connecting a vacuum pump to the exhaust connection 15 and the air inside the carton and the exhaust box 10 is then pumped out. Since the material which forms the sack 21 is extensible, the sack is forced into tight contact with the inner face of the walls 22 of the carton.

By referring to Figure 3 it will be seen that the end 23 of the expanded sack springs from a point 24 which is just below the fold line 25 of the bottom carton flaps. Consequently, by pushing a carton which has its bottom flaps extended into the exhaust box 10, it is possible to force the rubber sack directly against the walls of the carton and leave no fillet in the useable carton space which might later stress and tear the sack.

We next insert a liner 26. Preferably this is a slotted corrugated fibre board carton, the outside dimensions of which substantially equal the interior dimensions of the outer carton 16. The slots 28 at its corners are carried to approximately $\frac{1}{4}$ " above the score lines 29 which define the flaps 31, 31 and 32, 32. In addition, all four of its side walls are provided with fold lines 33, 33 or scores which extend not only along the walls of the liner 26 but also across the closing flaps 31, 31 and 32, 32. For this reason, if one pair of flaps 32, 32, for example, is folded into the liner first and down against its side walls and then flaps 31, 31 are pushed inwardly and downwardly into the liner in such a manner that the flaps 32, 32 are held down against the side walls, as shown in Fig. 5, the liner can be collapsed into the star shape shown in Fig. 6. In this collapsed condition the liner 26 is inserted into the rubber-lined outer carton 16 (see Fig. 7) and is then expanded as shown in Figure 8, so that the distribution of rubber is equalized and the sack 21 is uniformly held against all of the interior surface of the carton 16. Flaps 31, 31 are then turned down and after this flaps 32, 32 are turned down so that the bottom and side walls are

lined with the corrugated board. It is not essential that the bottom of the liner 26 be completely closed as long as it is sufficiently so to prevent damage to the sack 21. We prefer to use the box form of liner just described because there never is any difficulty in positioning various parts and because the final case is stronger but, obviously, separate lining pieces could be used.

10 The liner 26 holds the sack 21 securely in a fully expanded position and although the sack may try to shrink or collapse, it cannot. The valve is then closed so that the vacuum on the exhaust box 10 is broken and the lined carton is pulled out of the exhaust box 10 (Fig. 9). The fullness of the sack 21 is then pushed down behind the bottom flaps 17 which may then either be taped or machine sealed (Fig. 10).

We believe it the better procedure to expand 20 the sack 21 into a carton which has its bottom end flaps left open but it is possible, however, to expand the sack into a set-up carton and still reduce the fillet formed between the sack and the floor and walls of the carton to negligible 25 size if sufficient venting is provided and if the vents are so placed that the expanding sack cannot act as a valve and shut off the flow of air. Occasionally certain carton designs vent sufficiently without special precaution but it is 30 preferable because more certain to cut small vents in the four lower corners of the carton. With cut vents air from behind the fillet may be pumped out in nearly all cases and the fillet will practically disappear if the exhaust is continued to the necessary degree.

The lined carton is now loaded with a number 35 of retail packages 34 and when full the flaps 31, 31 and 32, 32 are bent down over the packages. If these contain fish, vegetables or meat, such 40 substances are better preserved if air is pumped out of the packages and the carton. This operation is performed in the following manner. The mouth portion 19 of the sack 21 is un-snapped from the carton 16 and its fullness 45 gathered about an evacuating nozzle 35 as shown in Fig. 12. When the air has been pumped out from the sack, the carton is twisted through several revolutions while the mouth part of the sack 21 is still gripped tightly against the vacuum nozzle 35. This operation forms a twisted seal as shown at 36 which experience has proved to be moisture and gas tight. Still holding the portion 36 against unwinding, the operator then 50 stretches it, as Fig. 14 shows, until the mouth 55 19 can be snapped over one of the top flaps 18 of the carton 16. Thereafter the seal cannot unwind. The opposing top flap is then turned in and the closing flaps are turned down. These 60 are sealed in any convenient manner. If air has not been removed from the container, the sack itself may be twisted to form the seal 36 and the remaining operations are performed as described.

In the case of frozen foods, the sealed 65 container is then placed in a sharp or a conventional freezer. Since all moisture is retained in the package and the only condensation which takes place comes from the moisture in the air, strawboard corrugated cartons are frequently 70 satisfactory and sufficiently waterproof to maintain their strength throughout the storage period. In certain freezers, however, particularly when much material is being moved in and out, condensation may cause too much softening of the strawboard. In that case, waterproofed or

dense millboard stock is preferable. Such packages may be stored for long times while stacked to considerable height without softening or bulging.

Assume, for example, that the completed package contains twenty-four 12-ounce retail packages of frozen peas and that this represents a retailer's unit purchase from the jobber. The package, just as it went into the freezer can, consequently, be delivered to the retailer. He may keep it in his own freezer without risk of deterioration until the last package is sold merely by untwisting the neck as each sale is made, taking out one retail package and then forming the seal again. By this means the packages may be protected against all desiccation and contamination up to the moment of sale; yet the heavy expense of wrapping each individual package in a vapor-proof manner is entirely eliminated.

As we have stated, we prefer to utilize formed bags for the liner. Where the package is not too large and the reduction in the thickness of the extensible material does not become too great, it is possible to practice this invention using flat sheets rather than a formed envelope. The margins of the sheets in this case are merely turned down and held against the top flaps of the carton. As the air is removed, the sheet stretches until a sack is formed which lies closely against the sides of the case.

For cigarettes and other articles, where the retention of moisture is important but which are not frozen, we utilize a material which has a lower transmission of moisture at room temperature than does latex-rubber. For such uses we prefer to use sheets or sacks of vulcanized rubber, or heat softened rubber hydrohalide, but polyvinyl acetals and other like materials are also useful.

From the above it will be apparent that we have described a new and extremely advantageous container and packaging method, many modifications of which will be apparent to those skilled in the art. We do not, therefore, desire to be limited to the embodiment of our invention hereinabove described for purposes of illustration, but only by the scope of the appended claims.

We claim:

1. A container comprising a shipping carton having top and bottom closing flaps, an open-mouthed sack of impervious sheet material placed against the set up walls of the carton and a lining placed within and coextensive with all portions of the sack disposed against the set up walls, said sack having a twisted neck portion

forming an air-tight seal and having its extreme mouth portion drawn over a flap of the carton, whereby the twisted neck of the sack is held against unwinding.

5 2. The process of lining a shipping container which comprises providing an open-ended receptacle having upstanding walls adapted to receive at least the open end flaps of a fibre shipping carton, snapping the open rim of an extensible vapor-impervious sack over the turned down top end flaps of the carton, exhausting the air in the receptacle and in the carton whereby the free air pressure forces the extensible material into contact with the interior walls 10 of the carton at least below the fold line of the bottom flaps, inserting a collapsed liner having a wall extent corresponding to the interior wall extent of the carton, removing the carton from the receptacle and sealing the bottom flaps.

20 3. The process of lining a shipping container which comprises covering an open end of a fibre shipping carton with a sack of extensible vapor-impervious material, forcing the extensible material into close contact with the interior walls 15 of the carton, inserting a liner having a perimeter and wall extent corresponding to the interior perimeter and wall extent of the carton and closing the bottom of the carton.

4. The process of lining a shipping container 30 with vapor-proof extensible material which comprises closing an end of the carton with a sheet of extensible material by engaging its margins with the margins of the carton, exhausting air from within the carton whereby the extensible material expands to cover and to lie closely against the upstanding walls of the carton permitting the material to expand until the wall portions of the sack so formed cover at least the permanent upstanding walls of the carton, inserting a liner within the sack and closing the bottom of the carton.

5. A container comprising a shipping carton having top and bottom closing flaps, an open-mouthed sack of extensible impervious sheet material placed against the set up walls of the carton and a lining placed within and coextensive with all portions of the sack disposed against the set up walls, said sack having a twisted neck portion forming an air-tight seal and having its extreme mouth portion drawn over a flap of the carton whereby the twisted neck of the sack is held against unwinding.
